UNITED STATES PATENT OFFICE.

VICTOR ALEXANDER RETTICH, OF NEW YORK, N. Y., ASSIGNOR TO KERN INCANDESCENT GAS LIGHT COMPANY, OF NEW YORK, N. Y., A CORPORATION OF NEW JERSEY.

REGULATING-VALVE FOR GAS-BURNERS.

SPECIFICATION forming part of Letters Patent No. 739,346, dated September 22, 1902.

Application filed November 11, 1901. Serial No. 81,841. (No model.)

To all whom it may concern:

Be it known that I, VICTOR ALEXANDER RETTICH, a subject of the King of England, and a resident of the borough of Manhattan, 5 in the city and State of New York, (post-office address, No. 124 West Ninety-seventh street, New York,) have invented certain new and useful Improvements in Regulating-Valves for Gas-Burners, of which the following is a specification, accompanied by drawings.

The invention is adapted and designed especially to the class of valves known in the gas-lighting art as "needle-valves," used in 15 burners of the Bunsen type, wherein the force of the gas issuing from the jet-orifice of the needle-valve is made use of to draw air into the mixing-chamber to produce a combustible mixture; but the invention is not limited 20 to this use, as it is applicable for regulating the jet-orifice of certain forms of acetylene-gas burners and is probably applicable to a good many other uses.

In use with incandescent mantles of the 25 Kern, Welsbach, and other types it is generally necessary for the purpose of obtaining the greatest efficiency for regulating the amount of gas according to the varying pressures and qualities of the gas met with in the 30 practical use of such burners. The invention offers a ready means of regulating the gas supplied to the burner in a highly-accurate and delicate manner and by a mechanism which is characterized by simplicity, 35 economy, cheapness, and freedom from leakage. In burners of this type it is not good practice to place a regulating-valve at some distance from the jet-orifice, because so to do reduces the gas-pressure at the orifice instead 40 of reducing the orifice without modifying the pressure. The present invention affords a means of regulating the freedom of passage through the orifice without necessarily in any way interfering with the freedom of the passage of the gas until it reaches the vicinity 45 of the orifice.

Briefly stated, the present improvement consists of a valve mechanism for the jet-orifice provided with extremely simple means 50 for adjusting the valve relatively to the ori-

fice, which means are described in the following portions of this specification, and the characteristic features are pointed out in the claims.

In the drawings, Figure 1 is a central section of a portion of one type of burner provided with my improvement. Fig. 2 is a side elevation of the needle-valve type illustrated in section in Fig. 1. Fig. 3 shows, partly in central section, a variation of the invention 60 employing a rack-and-pinion movement. Fig. 4 similarly shows another variation employing a snail or helical cam.

In Fig. 1 the mixing-tube or mixing-chamber of a Bunsen burner is shown at *b*, the air-inlet opening being indicated at *c*. The jet-orifice is shown at *d*. The jet-orifice *d* is preferably formed in a single piece with the gas connection *f*, by which the burner is fixed to the bracket or gas-pipe; but of course the invention is not concerned in the number of pieces which are employed to form any of the parts. Within the gas connection *f* is the gas passage-way *g*, through which the gas passes to the jet-orifice. This passage-way is usually screw-threaded for attachment to the gas-fixture. When so screw-threaded, I may utilize the threading as a means of inserting a stop *h* in the form of an incomplete wire ring, which is sprung into the threading, so as to prevent the dropping out of the valve when the adjusting connection or screw *j* is withdrawn. The valve *v*, preferably of the needle-valve type and fitted to the orifice *d*, is enlarged downward, and the enlarged portion in the preferred form of the invention is directly guided in the gas-duct or gas passage-way *g*. To permit free passage of the gas through the enlargement of the valve when designed in the form shown, ducts *w* are formed in the valve, as shown. Between the jet-orifice and the enlargement I prefer to employ a spring *s*, which acts independently of the weight of the valve to press the valve downward or away from the orifice. To furnish means for adjusting the valve mechanically, I prefer to employ a screw *j*, which is tapped or threaded through the wall of the gas connection and terminates internally in a conical or conoidal 95 100

end. This conoidal end forms an inclined surface, against which the valve rests and by means of which it may be elevated by screwing in the screw *j*; but I also prefer for an 5 inclined surface preferably a conical, spherical, or conoidal surface upon the valve, against which surface the end of the screw acts. By employing inclined surfaces on both the valve and the screw end a range of movement equal approximately to half the diameter of the screw plus the height of the incline on the valve is made possible. The screw *j* 10 not only forms a means of very delicate adjustment, but also affords one of the simplest 15 and best gas-tight joints through which the adjusting connection may pass. The complete mechanism constitutes a micrometer adjustment for the valve. The ring or stop *h* may be placed at such a point in the gas-passage as to 20 permit the valve to open as far as possible without interfering with the insertion of the screw into its hole, so that if the screw is withdrawn it can be reinserted without difficulty. The operation of this form of valve is such 25 that the gas is free to pass without loss of pressure directly to the orifice, and the valve merely controls the freedom of passage through the orifice and allows substantially the full pressure to act in forcing a jet of gas 30 through the orifice. The simplicity of construction obviates the necessity of separate ducts for passing around the larger portions of the valve and of any special guiding-surfaces for the valve. The invention utilizes 35 the wall of the gas-passage for guiding the enlarged portion of the valve. By merely taking out the screw and the stop *h* the valve and the spring *s* may drop freely out through the gas-passage, leaving the orifice free to be 40 cleaned from either direction.

In Fig. 3 the construction is varied by substituting a pinion upon the end of the screw, which engages a rack that moves with the valve, these elements taking the place of the 45 inclined surfaces of Figs. 1 and 2.

In Fig. 4 another variation is shown, in which the end of the screw is milled and the valve is provided with an inclined helical cam-surface or snail which the milled end of 50 the screw engages and supports. The rotation of the milled end of the screw rotates the valve and causes the cam or snail to elevate or depress the valve. The screw and the snail act like a small beveled gear coacting 55 with the beveled helical gear-wheel segment.

Other variations of the broader principles of the invention have suggested themselves; but the most approved form is shown in Figs. 60 1 and 2.

The invention admits of great simplicity and fewness of parts; but I am of course aware that the screw for giving passage to the adjusting connection through the wall of 65 the gas-passage need not necessarily be an integral part with the inclined surface or pinion

or other interior elements that more directly operate the valve.

In order to point out the characteristic and distinguishing features of my invention, I 70 claim the following:

1. In a burner apparatus of the type wherein the gas issues in a jet, the improvement which consists in the combination of a gas-conducting connection having a gas passage-way and 75 a jet-orifice, a valve for the jet-orifice provided with an enlargement having a gas-duct therein and which is guided in, and contained wholly within the passage-way, and a screw, threaded gas-tightly through the wall of the 80 gas connection its inner portion engaging part of the valve for supporting the same and adjusting it in said passage-way to regulate the freedom of passage at the jet-orifice.

2. In a burner apparatus of the type wherein 85 the gas issues in a jet, the improvement which consists in the combination of a gas-conducting connection having a gas passage-way and a jet-orifice, a valve for the jet-orifice provided with an enlarged portion movable with 90 it, a spring intermediate of the orifice and the enlargement and tending to press the valve away from the orifice, and means for adjusting the valve at will against the action of the spring, substantially as set forth. 95

3. In a burner apparatus of the type wherein the gas issues in a jet, the improvement which consists in the combination of a gas-conducting connection having a gas passage-way and a jet-orifice, a valve for the jet-orifice provided with an enlargement having a gas-duct therein and which is guided in the passage-way, a removable stop upon the wall of the 100 passage-way for engaging the enlargement and limiting its downward movement and 105 means for exteriorly adjusting the valve to regulate the freedom of passage at the jet-orifice.

4. In burner apparatus of the type wherein the gas issues in a jet, the improvement which 110 consists in the combination of a gas-conducting connection having a gas passage-way and provided with a jet-orifice, a valve for the jet-orifice movable to and from the orifice, and a gas-duct arranged to permit the passage 115 of gas by the lower portion of the valve, a rotary adjusting connection therefor screw-threaded substantially gas-tightly through the wall of the said gas connection and coöperating with the valve to raise and lower it 120 and regulate the jet, said adjusting connection having a conical end for translating its longitudinal motion into vertical adjustment of the valve.

5. In burner apparatus of the type wherein 125 the gas issues in a jet, the improvement which consists in the combination of a gas-conducting connection having a gas passage-way and provided with a jet-orifice, a valve for the jet-orifice movable to and from the orifice, 130 one of the parts having a gas-duct adapted for the passage of gas past the lower portion

of the valve and a rotary adjusting connection therefor screw-threaded substantially gas-tightly through the wall of the said gas connection and coöperating with the valve 5 to raise and lower it and regulate the jet, said adjusting connection working against a lower inclined surface of the valve for the purposes set forth.

6. In a burner apparatus of the type wherein 10 the gas issues in a jet, the improvement which consists in the combination of a gas-conducting connection having a gas passage-way and a jet-orifice, a valve for the jet-orifice provided with an enlargement, a gas-duct adapted

for the passage of gas past said enlargement 15 and an adjusting connection working longitudinally through the wall of the said gas connection and engaging a lower surface of the said enlargement inclined to the line of travel of the said adjusting connection for 20 raising and lowering the valve.

Signed this 9th day of November, 1901, at New York.

VICTOR ALEXANDER RETTICH.
